(57) **CLAIM**

(22) Filed: **Jul. 7, 1997**

The ornamental design for a holding and carrying device for
two handled shopping bags, as shown and described.

(51) LOC (7) Cl. **09-07**

DESCRIPTION

(52) U.S. Cl. **D9/434**

FIG. 1 is a front elevational view of a holding and carrying
device for two handled shopping bags, showing my new
design;

(58) Field of Search D8/300, 303; D9/344,
D9/434, 499; D7/622; D34/28; 16/110.1,
111.1, 406, 422; 248/95; 294/12, 137, 158,
159, 170, 171; 383/6, 13

FIG. 2 is a top edge elevational view thereof the bottom edge
elevational view being substantially identical thereto,
the sole variation being the orientation of the hook assembly at
each end;

FIG. 3 is a rear elevational view thereof; and,

FIG. 4 is a rear perspective view thereof.
